(57) **CLAIM**

The ornamental design for a wall protector, as shown and described.

DESCRIPTION

FIG. 1 is a front isometric view of a wall protector according to the present design.

FIG. 2 is a top plan view thereof;

FIG. 3 is a front elevational view thereof, the rear elevational view being a mirror image of FIG. 3;

FIG. 4 is a right side elevational view thereof, the left side view being a mirror image of FIG. 4;

FIG. 5 is a rear isometric view thereof; and,

FIG. 6 is a bottom plan view thereof, wherein the elements depicted by broken lines form no part of the claimed design.

1 Claim, 5 Drawing Sheets
